ATTORNEY

UNITED STATES PATENT OFFICE

167,828

RADIO RECEIVER CASING

Richard Florac, New York, N. Y., assignor to
Telanserphone Inc., New York, N. Y., a corpora-
tion of Delaware

Application May 27, 1952, Serial No. 19,908

Term of patent 14 years

(Cl. D56—4)

To all whom it may concern:

Be it known that I, Richard Florac, a citizen of the United States of America and a resident of New York, New York, have invented a new, original, and ornamental Design for a Radio Receiver Casing, of which the following is a specification, reference being had to the accompanying drawing, forming a part thereof.

Figure 1 is a perspective view of a radio receiver casing showing my new design.

Figure 2 is a rear elevational view thereof.

Figure 3 is a side elevational view thereof taken from the left side.

Figure 4 is a side elevational view thereof taken from the right side, and

Figure 5 is a bottom plan view.

I claim:

The ornamental design for a radio receiver casing, as shown.

RICHARD FLORAC.
